UNITED STATES PATENT OFFICE.

WILLIAM FRANK M. HAWE, OF PITTSBURGH, PENNSYLVANIA, ASSIGNOR TO MACBETH-EVANS GLASS COMPANY, OF PITTSBURGH, PENNSYLVANIA, A CORPORATION OF PENNSYLVANIA.

DESIGN FOR A LAMP-BOWL.

47,227.

Specification for Design.

Patented Apr. 13, 1915.

Application filed December 31, 1913. Serial No. 809,755. Term of patent 14 years.

To all whom it may concern:

Be it known that I, WILLIAM FRANK M. HAWE, a citizen of the United States, residing at Pittsburgh, in the county of Allegheny and State of Pennsylvania, have invented a new, original, and ornamental Design for Lamp-Bowls, of which the following is a specification, reference being had to the accompanying drawing, forming part thereof.

The figure is a perspective view of a lamp bowl, showing my new design.

I claim:

The ornamental design for a lamp bowl, as shown.

W. FRANK M. HAWE.

Witnesses:

J. A. CLARK,
HOWARD S. EVANS.
